FOOD CHOPPER FOR ONIONS OR THE LIKE

Efrem M. Ostrowsky, Highland Park, Ill., assignor to
Nibot Corporation, Chicago, Ill., a corporation of
Illinois

Filed Jan. 16, 1963, Ser. No. 73,195

Term of patent 14 years

(Cl. D89—1)

FIG. 1

FIG. 2

FIG. 1 is an elevational view of a food chopper for onions or the like, embodying my new design; and FIG. 2 is a top plan view thereof.

I claim:

The ornamental design for a food chopper for onions or the like, substantially as shown.
